VALVE ADJUSTING MEANS FOR INTERNAL COMBUSTION ENGINES

Original Filed Feb. 24, 1927

UNITED STATES PATENT OFFICE

ROBERT W. A. BREWER, OF JENKINTOWN, PENNSYLVANIA, ASSIGNOR TO HAROLD F. PITCAIRN, OF BRYN ATHYN, PENNSYLVANIA

VALVE-ADJUSTING MEANS FOR INTERNAL-COMBUSTION ENGINES

Application filed February 24, 1927, Serial No. 170,455. Renewed October 23, 1929.

This invention has reference primarily to such valve devices for internal combustion engines as are used, for example, in aeroplane or automobile work.

5 The first of the objects of this invention is the provision of a device of the character indicated which will be simple in construction, reliable in operation, not expensive to construct and which will permit necessary adjustments with certainty and accuracy and a minimum of trouble.

10 In order that the invention may be better understood, I will now proceed to describe the same in connection with the accompanying drawing showing it in preferred form, in which

15 Fig. 1 is a vertical sectional view thru the upper portion of an internal combustion cylinder showing a valve with my improvement applied thereto.

20 Fig. 2 is a transverse sectional view taken at right angles to the plane of the view shown in Fig. 1, at a point above the valve rocking lever and associated parts, and

25 Fig. 3 is a detailed sectional view taken on the line 3—3 of Fig. 1.

Referring now more particularly to Fig. 1, it will be seen that I have therein indicated at 4, the upper end of an internal combustion 30 cylinder provided with air cooling ribs 5.

The valve 6 has a stem 7, provided with a collar 8, and working inside of a bushing 9 and having seating springs 10 and 11.

35 Against the upper end of the valve stem 7 there is an actuating roller 12 carried in one of the forked ends of the rocking lever 13, the other end of which has a roller 14 constructed to contact with the upper head 15 of the vertically reciprocating member which bears 40 upon the rod 16 which latter in turn is actuated from some cam shaft or in other well known manner.

The rocker lever 13 is supported by a pivot pin 17, the ends of which are mounted in 45 cylindrical openings eccentrically disposed within the caps or bearings 18 which in turn are rotatable within the casing 19, as plainly indicated in Fig. 3.

50 As a convenient means for rotating the two bearing caps 18 in unison, I provide a rod

20 best shown in Fig. 2, which passes thru apertures in the caps 18, indicated at 21, is bent around so as to engage the oppositely disposed caps 18, and at the same time comes into engagement at 22 with a series of notches 55 23 formed in a rib 24 on the exterior of the casing 19 and of the adjacent portion of the cylinder structure, as indicated at 24, it being found preferable to split the chamber or casing which contains these parts along the 60 line 25 as indicated in Fig. 1.

The casing 19 which carries the supports for the cap pieces 18 is secured to the upper end of the cylinder casting by means of the bolt 26 in the manner indicated in Fig. 1, 65 and can be readily removed together with the adjusting handle 20.

It will be obvious that the mounting of the pin 17 within the cap bearing pieces 18 being eccentric to the cylindrical bearing of the 70 latter, any rotative movement of the caps 18 produced by manipulation of the handle 20 will shift the position of the rocking lever 13 and change the adjustment of the rollers 12 and 14 with reference to their coacting parts 75 and the handle 20 being on the outside of the casing, adjustments can be readily made without taking the members apart, there being sufficient spring in the handle 20 to permit it to be shifted from one notch to another along the row of notches 23.

While the handle 20 will itself aid in keeping the cap bearing pieces 18 in position, I provide as an additional safety device the set screws 27 arranged to engage slots 28 in the 85 cap pieces 18 in such manner as will resist any tendency of the cap pieces to work out of their bearings endwise.

In making adjustments in service with my improved adjusting device, all that is necessary is to move the handle 20 along the notches 23 until the rollers 12 and 14 come in contact with their coacting parts and then to provide proper amount of clearance by simply moving the handle backward one or 95 more notches as desired, the notches being dimensioned and arranged on the rib 24 in predetermined position so that exactly the desired amount of clearance will be obtained from a given or predetermined amount of 100

movement. This can obviously be done without taking any of the mechanism apart and without the necessity of unscrewing any bolts or retaining members or cap screws as is required in many adjusting devices in common use.

It is also evident that in my improved adjusting mechanism all of the actuating parts are thoroughly and efficiently encased and protected while the adjusting device itself is upon the outside of the casing and readily accessible at all times not only for adjustment but also for inspection.

I claim:—

- 15 1. In combination a valve, a valve rocker, a valve actuating rod, an adjustable mounting for said rocker, a casing enclosing said rocker and means outside said casing for effecting manual adjustment of said rocker, including a member adapted to engage the casing to hold the rocker in adjusted position said member being resilient to enable its being disengaged from the casing when adjustment is to be effected.
- 20 2. In combination a valve, a valve rocker, a valve actuating rod, an adjustable mounting for said rocker, a casing enclosing said rocker, means outside said casing for moving said rocker mounting, means carried by the casing engageable by said moving means to lock the mounting in its moved position, said moving means being resilient.
- 25 3. In combination a valve, a valve rocker having a fulcrum pin, a valve actuating rod, a movable eccentric mounting for the pin, a support for said eccentric mounting, a resilient rod for moving said eccentric mounting and means carried by a fixed part with which said rod is adapted to have snap engagement to hold the mounting in its moved position.
- 30 40 4. In testimony whereof I have hereunto signed my name.

ROBERT W. A. BREWER.
